UNITED STATES PATENT OFFICE.

CHARLES A. APPEL, JR., OF WASHINGTON, DISTRICT OF COLUMBIA.

CHECK-PROTECTOR.

1,384,584.

Specification of Letters Patent. Patented July 12, 1921.

Application filed May 17, 1921. Serial No. 470,435.

To all whom it may concern:

Be it known that I, CHARLES A. APPEL, Jr., a resident of Washington, District of Columbia, a citizen of the United States, 5 have invented certain new and useful Improvements in Check-Protectors, of which the following is a specification.

This invention has for its object the provision of a check protector of simple construction and low cost, which will need no special adjustment when it is to be used, and which will be highly efficient to prevent alteration in a check.

The invention is illustrated in the accompanying drawings, wherein corresponding numerals of reference are used to indicate corresponding parts in the several views.

In the drawings—

20 Figure 1 is a plan view, with parts broken away and in section, of a device embodying the invention;

Fig. 2 is a longitudinal section of the device;

25 Fig. 3 is a transverse section on the line 3—3 of Fig. 1; and

Fig. 4 is a fragmentary sectional view showing a modification.

In carrying out the invention I employ 30 a base plate 1, having upstanding flanges 2, at its side edges and at one end, the opposite end being inclined upwardly and outwardly, as shown at 3 and terminating in an eye 4. Upon this base plate, between 35 the side flanges 2, and extending nearly the full length of the plate, I place a pad 5, of rubber or other cushioning material having its upper surface flush with the upper edges of the flanges, and filler blocks 40 6, of any convenient firm material are fitted upon the base plate at the ends of the pad so that the pad will be held against moving by the flanges and said blocks.

I also employ a guide plate 7 which rests 45 at one end upon the filler block 6 and has said end constructed to bear upon the portion 3 of the base plate immediately adjacent the eye 4, as shown at 8. The guide plate is preferably of sheet metal in order to 50 be light and durable and is constructed with fine perforations 9, throughout its area over the pad 5, the guide plate being spaced vertically from the pad, as shown in Fig. 2.

The guide plate constitutes the bottom 55 of an upper frame or casing 10, having an opening 11 in its top which is nearly equal

in extent to the pad 5. One end wall 12 of the upper casing unites the top with the free end of the guide plate, while the opposite end, 13, is inclined downwardly and 60 terminates in an eye 14 in contact with the eye 4. The eyes 4 and 14 may be soldered or otherwise intimately united and furnish a convenient means for suspending the device upon a support when it is not in use. 65

Within the upper frame or casing 10, and extending entirely across the opening 11, is a sheet 15, of rubber or other highly flexible or elastic material which is supported by and forms a cover for a multiplicity of small 70 pins 16, which have their points arranged to work through the perforations 9, in the guide plate 8. The pins are provided with heads 17, the upper surface of the heads being preferably flat, upon which the flexible sheet 15 directly rests, the lower ends of the heads presenting shoulders which bear upon the upper side of a carrier 18, consisting of a spring plate extending longitudinally of the casing or upper frame and 75 having its ends formed with longitudinal slots 19, through which pass rivets 20, whereby the spring is secured in place. The spring plate or carrier is constructed 80 with perforations 21, which register respectively with the perforations 9 and through which the pins depend.

The use of the device will be readily understood. The blank check is inserted 90 between the pad 5 and the guide plate and will lie upon the former. The drawer of the check then takes a stylus, pencil, or other similar device, and writes upon the flexible sheet 15, the amount to be paid upon presentation of the check at the proper 95 bank. The carrier 18 readily yields to a slight pressure, so that, as the stylus or other implement passes over the sheet 15, the pin immediately under the implement will be depressed and caused to puncture or perforate the check, the successive punctures forming the letters or figures traced on the flexible sheet 15, by the implement. It will thus be seen that the amount for which the check is drawn will be perforated in 100 or through the check and any attempted alteration in the amount will be readily detected.

It will be understood, of course, that the name of the drawer, that is his signature, 110 or the name of the payee may be likewise perforated in the check.

In Fig. 4, a spring 25 is coiled around each pin 16, between the guide plate 7 and the spring carrier, thereby aiding in the withdrawal of the depressed pins so that 5 tearing of the check will be avoided.

It will be readily noted that no adjustment of the device is necessary when it is to be used and that the work of drawing a check is no greater than that required 10 in writing a check by hand as generally practised.

Having thus fully described my invention, what I claim as new and desire to secure by Letters Patent of the United 15 States, is—

1. A check protector comprising a support for the check to be drawn, and a multiplicity of puncturing devices adapted to be individually actuated and over which a 20 stylus may travel as in the act of writing.

2. A check protector comprising a pad to support a blank check, a multiplicity of pins yieldably supported above the pad, and

a flexible sheet extending over and resting on the pins and over which a stylus may 25 travel as in the act of writing.

3. A check protector comprising a pad to support a blank check, a perforated guide plate supported over the pad in spaced relation thereto, a multiplicity of pins yieldably mounted above the guide plate and playing through the perforations therein, and a flexible sheet covering the pins and over which a stylus may travel to depress the 30 pins as in the act of writing.

4. A check protector comprising a pad, a guide plate supported over the pad in spaced relation thereto, a resilient carrier above the guide plate, and a multiplicity of pins supported by the carrier and playing 40 through the guide plate and adapted to be successively depressed by a stylus as in the act of writing.

In testimony whereof I hereunto affix my signature.

CHARLES A. APPEL, JR.
